[57] CLAIM

The ornamental design for a baby bottle, as shown.

DESCRIPTION

FIG. 1 is a perspective view of a baby bottle, showing our new design;

FIG. 2 is a right side elevational view thereof, the left side elevational view being identical thereto;

FIG. 3 is a top plan view thereof;

FIG. 4 is a bottom plan view thereof;

FIG. 5 is a front elevational view thereof; and

FIG. 6 is a rear elevational view thereof.

FIG. 1
